APPARATUS FOR COUNTER-CURRENT
EXTRACTION

André Olier, Clermont-Ferrand, France, assignor
to Société Anonyme des Etablissements A.
Olier, Usines Saint-Rémy, France

Application June 22, 1933, Serial No. 677,073
In France July 18, 1932

1 Claim. (Cl. 87—28)

It sometimes happens to be of great importance to withdraw a liquid at a point situated at a determined distance from the upper level of the liquid. It is chiefly the case when exhausting certain material, this material being for instance beet slices downwardly circulating in a liquid this latter being movable in the contrary direction. The concentration of this liquid is hence maximum at the surface thereof. But the level of this surface is not constant chiefly because of variations of the speed of the material to be exhausted and of the liquid itself on one hand, and of the porosity of this material on the other hand.

This also occurs in the case of two superposed layers of liquid (any suitable liquid covered by a layer of a protecting liquid) and namely then when it is desired to withdraw the liquid of the lower layer at its upper level.

The present invention has for its object to provide for a device for the withdrawal of liquids, the withdrawal taking place at a constant distance from the variable upper level of the liquid.

According to one feature, the device comprises a float and a discharge element for the liquid connected with said float at a point situated at a determined distance from the floating plane of the said float.

Other features of the invention will be set forth in the following description.

In the accompanying drawing, which is given solely by way of example:

Fig. 1 is a vertical lengthwise section of a device according to the invention, applied, for example, to the case of the continuous diffusion process for extracting sugar containing substances from beets and sugar cane, or fatty substances from oleaginous grains or oil-cake, etc. . . .

Fig. 2 is a corresponding side view.

Fig. 3 is a section on the line 3—3 of Fig. 2. Fig. 4 shows in a detailed way the method of mounting the plates on the chains.

According to the example of construction herein represented, the device comprises an exhausting column 1 containing a number of perforated discs 2 mounted on calibrated movable chains 3. Said chains are driven by any suitable means and cause said discs to move in the direction of arrow f^1 . The discs carry the material or substance to be treated.

A receptacle 4 is mounted laterally with respect to column 1, wherefrom it is separated by a perforated wall 5. The bottom of receptacle 4 carries secured thereto a tube 6 provided with

side-neck 7. A pipe 8 enters the tube 6 and is provided at its upper part with an orifice 9. Pipe 8 is moreover secured to a float 10. The choice of the length of pipe 8 is so made as to cause this latter to constantly remain within tube 6 whatever the vertical movements of the float 10 may be. A stuffing-box 11 is provided between tube 6 and receptacle 4 in order to prevent all direct flow of the liquid from this receptacle into the tube.

The operation of the above described device is the following. After they have been charged with the material to be treated the discs descend, as above mentioned, in the direction of arrow f^1 . The liquid for the exhaust of the material carried by discs 2 is supplied to the lower part of column 1, and moves in the contrary direction according to arrow f^2 . This movement can be obtained by means of a static load. The liquid adapted to dissolve or to exhaust the material on the discs becomes thus gradually enriched, and is transformed into an extract. Should the static load be constant, the level of the liquid in column 1 will depend either upon the relative speed of the liquid and the material to be treated or upon the porosity of the piled up material and carried by the discs. As the richest part of the liquid always remains in the variable region marked X—X and as this region is adjacent the lower part of the fresh material immersed in the liquid, the best withdrawal of the liquid will therefore take place at this variable level X—X. The distance between variable level X—X and the variable upper level Y—Y is obviously constant, and therefore the distance between float 10 and orifice 9 may be so adjusted as to have orifice 9 always situated adjacent level X—X. The liquid will be thus discharged through orifice 9, pipe 8, tube 6 and neck 7.

It is obvious that the float may have any suitable form, and it is not necessary to cause it to remain upon the surface of the liquid; it may of course be half submerged, or disposed in any other suitable way. Thus in the case of two liquids which are not miscible, if it is desired to withdraw, at the surface, solely the lower liquid of greater density, the float will be so constituted and its weight so chosen as to cause it to float upon the lower liquid.

By the use of the device herein described, the efficiency of the apparatus is greatly increased by avoiding all loss of space, because of the withdrawal being rendered independent of the level, contrary to what happens in the case of a sta-

tionary orifice, where the withdrawal of the liquid is intermittent should it be desired to take the liquid at a point situated quite near the surface of this liquid.

5 Obviously, the invention is not limited to the form of construction herein described and represented, which is given solely by way of example.

Having now described my invention what I claim as new and desire to secure by Letters 10 Patent is:

In an apparatus for counter current extraction, for the treatment of beet slices, oleaginous materials and the like, the combination of a column adapted to contain the exhausting 15 circulating liquid, a number of perforated plates

adapted to carry the material to be exhausted and suitably supported and guided within said column for movement therein, a container located along said column and in communication therewith through a perforated wall, a stuffing 5 box at the bottom of said container, a float in said container, a floating pipe supported by said float and adapted to slide through said stuffing box and a stationary discharge pipe in which the floating pipe is adapted to extend, the floating pipe being provided with a discharge orifice located at a predetermined distance with respect to the floating plane of said float.
